UNITED STATES PATENT OFFICE.

NORMAN DODGE, OF EAST ORANGE, NEW JERSEY, ASSIGNOR TO MERGENTHALER LINOTYPE COMPANY, A CORPORATION OF NEW YORK.

TYPGRAPHICAL MACHINE.

1,129,176.

Specification of Letters Patent. Patented Feb. 23, 1915.

Application filed November 3, 1914. Serial No. 870,019.

To all whom it may concern:

Be it known that I, NORMAN DODGE, a citizen of the United States, residing at East Orange, in the county of Essex and 5 State of New Jersey, have invented certain new and useful Improvements in Typographical Machines, of which the following is a specification, reference being had therein to the accompanying drawing.

10 My invention relates to typographical machines, such as linotype machines of the general organization represented in Letters Patent of the United States No. 436,532, to O. Mergenthaler, wherein circulating 15 matrices are released from a magazine in the order in which their characters are to appear in print and then assembled in line, the composed line transferred to the face of a mold, the mold filled with molten metal 20 to form a slug or linotype against the matrices which produce the type characters thereon, and the matrices thereafter returned through distributing mechanism to the magazine from which they started.

25 More particularly, it relates to such machines when equipped with double or Janus-faced matrices, that is to say, matrices formed with a plurality of characters in each of their opposite edges, together with 30 means for determining the level of the matrices, matrix-reversing means, and common devices for controlling the operation of both said last mentioned means.

35 Machines provided with matrix-reversing means such as those referred to are illustrated in Letters Patent of the United States to Holbourns and Longhurst, No. 951,948, and in the application for Letters Patent of D. S. Kennedy, filed February 21, 40 1914, Serial No. 820,194.

45 It is frequently the practice in the use of linotype machines to make long runs on certain classes of work where two different faces are mixed in the same line, as for example in telephone directories and the like, where the names and addresses are given in a light face type and the numbers and exchange names in a black face. The specific embodiment of my invention permits 50 the shifting of the matrix-reversing means simultaneously with the adjustment of the means for determining the level of the matrices, this result being secured without special attention or care on the part of the

operator, and without the liability to imperfect results which would arise in the event that the several devices were not correspondingly adjusted. The particular class of work cited is mentioned only by way of example, as obviously my improvements 60 will be equally applicable in many cases where it is desired to reverse the matrices and also employ them at different levels, and particularly where the composite shift is frequently necessitated.

65 In the accompanying drawings, I have shown my invention only in preferred form, but obviously many changes and variations may be made therein, and in its mode of application, which will still be comprised 70 within its spirit. Similarly it may be applied to other forms of typographical machines, such as typesetters, typecasters and the like, which handle type or dies, instead of matrices. Generally speaking, I desire 75 it to be understood that I do not limit myself to any specific form or embodiment, except in so far as such limitations are specified in the claims.

80 Referring to the drawings: Figure 1 is a perspective view of a portion of a linotype machine with my improvements embodied therein; Fig. 2 is a vertical section through the assembler; Figs. 3, 4 and 5 are similar views showing the parts in different 85 positions; and Fig. 6 is a perspective detail.

85 As is usual, the matrices X are released by the manipulation of the keyboard R and delivered to the assembler belt S, from 90 which they pass into the assembler T. After the line is composed, the assembler is raised and the line transferred therefrom through the intermediate channel W, from 95 which in turn it passes to the casting devices. When Janus-faced matrices are employed, their position is controlled by suitable reversing means, such for instance as the device A, which receives them from the belt S and through which they pass into 100 the assembler. As in the said Holbourns and Longhurst patent and the Kennedy application, this device is provided with two throats, one a straight or plain channel to deliver the matrices unreversed, and the 105 other a tortuous or rifled channel to reverse them in their passage to the line. In Fig. 1 herein the upper or reversing channel A

is shown in operative relation to the other parts.

In the present instance the reversing device A is slidably mounted in the frame and is normally forced upward by the spring A² so as to bring the straight or plain channel into operation, but it may be moved in the opposite direction to bring the rifled or reversing channel into position by the finger key B and the connected link C. The key B is located in convenient proximity to the keyboard R, and the link C is suitably inclined (see dotted lines) and formed to engage the end of the pivoted arm D, the link being preferably provided with a roller C¹ to bear upon the nose or outer end of the arm. The arm D passes transversely across the upper portion of the reversing device A, and is located above a stud A¹ on the latter, the arm being formed with a plurality of notches D¹ to engage the stud in the several operative positions. Normally the spring A² holds the device A, arm D, link C, and key B in their uppermost positions, but when the key is actuated, the link C depresses the arm and the reversing device so as to bring the channel A¹ into operation, as indicated in Fig. 1. The key B may then be engaged with a notch or cut B¹ in the framework to hold the several elements against the tension of the spring A². The parts so far described are or may be of any ordinary construction, such for instance as that presented in the Kennedy application, and in themselves constitute no part of my present invention, except as hereinafter specified.

The assembler T is provided as usual with the two movable blades E and F, whereby the level of the matrices and consequently the selection of the characters in their operative edges is determined. The former acts to arrest the matrices in their elevated position and the latter to retain them there, the respective blades being provided with the adjusting levers E¹ and F¹, all in the manner well understood in the art. However, in the present instance I have provided connections whereby the blades are adjusted by the movement of the previously mentioned key B, so that when the latter is operated to reverse the matrices, their level in the assembler will be simultaneously controlled. These means preferably comprise the plate G mounted upon the vertical rocking frame H, the plate being formed with a notch G¹ to engage the lever E¹ of the blade E, and with a notch G² to engage the lever F¹ of the blade F, so that when the frame H is swung in one direction, the blades will be projected into the assembler, and when moved in the opposite direction they will be withdrawn therefrom. The plate G is slidably mounted upon the frame H, and the notches G¹ and

G² therein are so formed, that when desired the plate may be slid to inoperative position and out of engagement with the levers E¹ and F¹, thus breaking the connection between the blades and the matrix-reversing means and permitting the use of the machine in the ordinary manner.

The connections between the swinging frame H and the reversing key B comprise a pair of vertical arms J and K connected to the frame and located at opposite sides of its pivotal point, and a sliding piece L mounted on the key which may be moved thereon to engage either of the two arms and thus swing the frame in opposite directions according to its location. The slide L is formed with two oppositely projecting arms N and O, the former adapted to enter between and engage the projections J¹ and J² on the arm J, and the latter to enter between and engage the projections K¹ and K² on the arm K, according to the position of the slide L. The means for adjusting the slide L preferably comprise the finger lever M pivoted to the key B and connected by the link L¹ to the slide.

In Figs. 2 and 4 the lever M is shown in its uppermost position with relation to the key B, and the arm N in operative relation to the projections J¹ and J², while in Figs. 3 and 5 the lever M is shown in its lowermost position, and the arm O in operative relation to the projections K¹ and K². If the lever M be moved to intermediate position (see dotted lines in Fig. 4), the slide L will be so positioned as to locate both its arms N and O entirely out of operative relation to the arms J and K, in which circumstances the actuation of the key B effects only the reversal of the matrices, and the determination of their level will depend upon the manipulation of the lever E¹, all in the ordinary manner.

The operation of my improvements will now be clearly understood. Referring first to Fig. 2, it will be noted that the key B is in normal position and the arm N in engagement with the projection J¹ on the arm J, which condition results in the delivery of the matrices unreversed and the retraction of the blade E, so as to bring the upper character 1 into operation. If now the key B be depressed (Fig. 4), the device A is adjusted to reverse the matrices, and due to the action of the arm N on the projection J², the blade E is projected into the assembler, thus bringing the lower character 4 into operation. In other words, the actuation of the key B has effected a change from the upper character on one edge of the matrix to the lower character on the opposite edge. Referring to Fig. 3, the key B is in its uppermost position and the arm O of the slide L in engagement with the projection K¹, which condition of the parts re-

sults in the delivery of unreversed matrices, and the projection of the blade E into the assembler, thus rendering the character 2 operative. If the key B be depressed (Fig. 5), the device A is shifted so as to reverse the matrices, and due to the action of the arm O on the projection K², the blade E is withdrawn from the assembler, thus resulting in the delivery of reversed matrices to their lowermost position in the assembler, and bringing the upper character 3 into action. In this instance, the actuation of the key has effected a change from the lower character on one edge of the matrix to the upper character on its opposite edge. If it be desired to operate the parts in the ordinary manner, so as to secure any combination of characters, this may be effected by interrupting the connection between the reversing key and the movable assembler blades, either by adjusting the slide G or the slide L to inoperative position, as previously described.

As previously stated, I have shown my invention only in preferred form and by way of example, and as applied to a particular form of mechanism. However, many modifications and alterations therein, as well as in its mode of adaptation, will suggest themselves to those skilled in the art, without departure from its scope.

Having thus described my invention, its construction and mode of operation, what I claim and desire to secure by Letters Patent of the United States, is as follows:

1. In a typographical machine, the combination of an assembler adapted to support matrices at different levels therein, means for determining the level of the matrices, matrix-reversing means, and common devices for controlling the operation of both said means.

2. In a typographical machine, the combination of an assembler adapted to support matrices at different levels therein, matrix-reversing means, and devices controlled by said means for determining the level of the matrices in the assembler.

3. In a typographical machine, the combination of an assembler adapted to support matrices at different levels therein, a movable switch to determine the level of the matrices, a movable matrix reversing chute, and connections between said chute and

switch to insure their corresponding movements.

4. In a typographical machine, the combination of an assembler provided with a movable switch or blade to arrest the incoming matrices in elevated position therein, a movable matrix-reversing chute, and connections between said chute and blade to insure their corresponding movements.

5. In a typographical machine, the combination of an assembler provided with a switch or blade to arrest the incoming matrices in elevated position therein, a movable matrix-reversing chute, and a finger key connected to both said chute and blade for controlling their movements.

6. In a typographical machine, the combination of an assembler adapted to support matrices at different levels therein, a movable switch to determine the level of the matrices, a movable matrix-reversing chute, and a finger key connected to both said switch and chute for controlling their movements.

7. In a typographical machine, the combination of an assembler provided with a movable blade to support the matrices in elevated position therein, a movable matrix-reversing chute, and connections between said chute and blade to effect their corresponding movements.

8. In a typographical machine, the combination of an assembler adapted to support matrices at different levels therein, means for determining the level of the matrices, matrix-reversing means, and mechanism whereby the two said means may be operated conjointly or independently, as desired.

9. In a typographical machine, the combination of an assembler adapted to support matrices at different levels therein, a movable switch to determine the level of the matrices, a movable matrix-reversing chute, connections between said chute and switch to insure their corresponding movements, and means for breaking said connections at will.

In testimony whereof, I have affixed my signature in presence of two witnesses.

NORMAN DODGE.
